UNITED STATES PATENT OFFICE

170,076

DEVOTIONAL DESK

Elizabeth Alberta Brenner, Wallingford, Conn.

Application December 30, 1952, Serial No. 22,937

Term of patent 14 years

(Cl. D29—23)

To all whom it may concern:

Be it known that I, Elizabeth Alberta Brenner, a citizen of the United States, residing at Wallingford, county of New Haven, State of Connecticut, have invented a new, original, and ornamental Design for a Devotional Desk, of which the following is a specification, reference being had to the accompanying drawings, forming a part thereof, in which

Fig. 1 is a front perspective view of a devotional desk showing my new design;

Fig. 2 is a rear perspective view thereof, and
Fig. 3 is a side perspective view thereof.

The essential features of my design reside in those portions shown in full lines.

I claim:

The ornamental design for a devotional desk, as shown and described.

ELIZABETH ALBERTA BRENNER.
